(57) **CLAIM**

The ornamental design for a driverless signage flag, as shown and described.

DESCRIPTION

FIG. 1 is a front perspective view of a driverless signage flag, showing a first embodiment of my new design;

FIG. 2 is a rear perspective view of FIG. 1;

FIG. 3 is a front elevational view of FIG. 1;

FIG. 4 is a rear elevational view of FIG. 1;

FIG. 5 is a left-side elevational view of FIG. 1;

FIG. 6 is a right-side elevational view of FIG. 1;

FIG. 7 is a top plan view of FIG. 1, the bottom plan view being a mirror image thereof;

FIG. 8 is a front perspective view of a second embodiment thereof;

FIG. 9 is a rear perspective view of FIG. 8;

FIG. 10 is a front elevational view of FIG. 8;

FIG. 11 is a rear elevational view of FIG. 8;

FIG. 12 is a left-side elevational view of FIG. 8;

FIG. 13 is a right-side elevational view of FIG. 8;

FIG. 14 is a top plan view of FIG. 8, the bottom plan view being a mirror image thereof;

FIG. 15 is a front perspective view of a third embodiment thereof;

FIG. 16 is a rear perspective view of FIG. 15;

FIG. 17 is a front elevational view of FIG. 15;

FIG. 18 is a rear elevational view of FIG. 15;

FIG. 19 is a left-side elevational view of FIG. 15;

FIG. 20 is a right-side elevational view of FIG. 15; and,

FIG. 21 is a top plan view of FIG. 15, the bottom plan view being a mirror image thereof.

The broken lines showing a header and a logo in the figures depict portions of the driverless signage flag that form no part of the claimed design.

1 Claim, 15 Drawing Sheets
